UNITED STATES PATENT OFFICE.

ALBERT LEIGHTON, OF ST. LOUIS, MISSOURI.

COMBINED SUSPENDER-BELT TAB AND BELT-LOOP FOR TROUSERS.

Specification of Letters Patent. Patented Feb. 19, 1918.

1,256,580.

Application filed May 16, 1917. Serial No. 169,125.

To all whom it may concern:

Be it known that I, ALBERT LEIGHTON, a citizen of the United States, and a resident of St. Louis, Mo., have made a new and useful Improvement in a Combined Suspender-Belt Tab and Belt-Loop for Trousers, of which the following is a specification.

This invention relates to a combined suspender, suspender tab and belt loop for use 10 on men's trousers whereby the same may be easily converted or adapted for use as suspenders or belt as desired, and is directed more particularly to certain improvements 15 over the construction shown in my prior Patent 1,105,355, July 28, 1914.

One of the objects of the present invention is to provide a combined suspender tab and belt loop together with coacting member such as the suspender webbing therefor 20 which may be easily and quickly applied to trousers, overalls and the like, whereby the same may be supported either as a belt or suspenders as desired; the same webbing serving both purposes.

Another object is to provide a simple and practical device of the above general character which will be inexpensive to manufacture.

Other objects will be in part obvious from 30 the annexed drawings and in part indicated in connection therewith by the following analysis of this invention.

This invention accordingly consists in the features of construction, combination of 35 parts and in the unique relations of the members and in the relative proportioning and disposition thereof, all as more completely outlined herein.

To enable others skilled in the art so fully 40 to comprehend the underlying features thereof that they may embody the same by the numerous modifications in structure and relation contemplated by this invention, drawings depicting a preferred form have been 45 annexed as a part of this disclosure, and in such drawings like characters of reference denote corresponding parts throughout all the views, in which

Figure 1 is a perspective view showing 50 trousers with a suspender strap applied thereto;

Fig. 2 is a detail view showing how the suspender may be conveniently tightened;

Fig. 3 is a similar view showing one of the front straps;

Fig. 4 is a similar view showing the use of the device as a belt.

Referring now to the drawings in detail, there is illustrated at A the waist band to which supporting tabs B are adapted to be 60 attached. This band may be secured bodily to the overalls or trousers or may be directly applied to the trousers as indicated in my prior patent. Along the upper edge are two fastening means such as eyelets d (Fig. 2) 65 spaced apart approximately an inch or an inch and a half on the belt band through which cords e are adapted to be passed. These eyelets may however be any suitable form of fastening means adapted to secure 70 the ends of the cords. The other ends of the cords terminate in a single member b having an elongated loop through which a single piece of suspender webbing a is adapted to 75 pass as herein shown in Fig. 1. This tab is particularly adapted for use at the rear of the trousers and the suspender may be tightened or otherwise adjusted by means of a link f as shown in Fig. 2.

In Fig. 3 the device is substantially the 80 same as that above described except that the member b is provided with a narrower opening h through which the front end of one of the suspender straps forming a fastening member i is adapted to pass before being 85 snapped into place as shown. All of these tabs are provided with a socket in the member b which may be snapped down over a head e as shown in Fig. 4, thereby providing a belt loop through which the webbing 90 may be passed as indicated in this figure. The fasteners i constitute attaching means for the ends of the webbing when used as a belt.

From the above it will be seen that the 95 article is easily and quickly convertible from one use to the other as desired and enables the manufacturers of trousers to dispense with the sewing on of buttons and tapes for belts with the consequent saving in time and 100 material.

I realize that considerable variation is

possible in the details of construction and arrangement of parts without departing from the spirit of my invention, and I therefore do not intend to limit myself to the specific form shown and described.

Having thus described my invention what I claim as new and desire to secure by Letters Patent is:

In combination with a waist band, an attachment therefor comprising a pair of flexible members each secured at one end to said

waist band, complementary fastening means on said members and waist band whereby the same may form belt loops, and a suspender strap having fastening means at its ends adapted to co-act with the fastening means on said flexible members when the strip is used as suspenders or with each other when the strap is used as a belt after being passed through the said belt loops.

(Signed) ALBERT LEIGHTON.
